CLAIM

The ornamental design for a smart speaker, as shown and described.

DESCRIPTION

FIG. 1 is a front elevation view of a smart speaker; FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is a third perspective view thereof; and,

FIG. 10 is a fourth perspective view thereof.

The broken lines shown in the drawings depict portions of the smart speaker that form no part of the claimed design.

1 Claim, 10 Drawing Sheets
